US0D1114089S

(12) **United States Design Patent** (10) **Patent No.:** **US D1,114,089 S**
(45) **Date of Patent:** **** Feb. 17, 2026**

(54) **MODEL VEHICLE BUMPER**

(71) Applicant: **TRAXXAS, L.P.**, McKinney, TX (US)

(72) Inventors: **Skylar Hagler**, Anna, TX (US); **Jory Sprowl**, Howe, TX (US); **Otto Karl Allmendinger**, Rowlett, TX (US); **Adam Cole Ewing**, McKinney, TX (US); **Kent Poteet**, Lucas, TX (US)

(73) Assignee: **TRAXXAS, L.P.**, McKinney, TX (US)

(**) Term: **15 Years**

(21) Appl. No.: **29/936,783**

(22) Filed: **Apr. 10, 2024**

(51) LOC (15) Cl. **21-01**

(52) U.S. Cl.

(57) **CLAIM**

The ornamental design for a model vehicle bumper as shown and described.

DESCRIPTION

FIG. 1 is an upper, left, front perspective view of a model vehicle bumper showing our new design;
FIG. 2 is an upper, right, rear perspective view thereof;
FIG. 3 is a lower, right, front perspective view thereof;
FIG. 4 is a lower, left, rear perspective view thereof;
FIG. 5 is a front elevation view thereof;
FIG. 6 is a rear elevation view thereof;
FIG. 7 is a right-side elevation view thereof;
FIG. 8 is a left-side elevation view thereof;
FIG. 9 is an upper plan view thereof; and,
FIG. 10 is a lower plan view of the model vehicle bumper. In the drawings, the broken lines illustrate portions of the model vehicle bumper that form no part of the claimed design.

1 Claim, 7 Drawing Sheets
